(57) CLAIM

The ornamental design for a convertible tote and backpack, as shown.

DESCRIPTION

FIG. 1 is a perspective view of a convertible tote and backpack;

FIG. 2 is a front view of the convertible tote and backpack;

FIG. 3 is a rear view of the convertible tote and backpack;

FIG. 4 is a right side view of the convertible tote and backpack;

FIG. 5 is a left side view of the convertible tote and backpack;

FIG. 6 is a top view of the convertible tote and backpack; and,

FIG. 7 is a bottom view of the convertible tote and backpack as a tote.

The broken line elements in all views are for illustrative and environmental purposes only and form no part of the claimed design.

1 Claim, 5 Drawing Sheets
